UNITED STATES PATENT OFFICE.

FREDERICK CARLISLE OWEN, OF FAYETTEVILLE, NORTH CAROLINA.

INDUCTIVE WATER HEATER.

Application filed October 28, 1926. Serial No. 144,818.

This invention relates to inductive heaters, and has for one of its objects to provide a novel, highly efficient and practical device of this character through the medium 5 of which water may be rapidly heated to the required degree at a comparatively low cost.

With the foregoing and other objects in view, the nature of which will become apparent as the description proceeds, the invention consists of the construction, combination and arrangement of parts hereinafter fully described and claimed, and illustrated in the accompanying drawings, wherein:

15 Figure 1 is an elevational view of an inductive water heater constructed in accordance with my invention,

Figure 2 is a detail sectional view taken on the plane indicated by the line 2—2 of 20 Figure 1,

Figure 3 is a similar view taken on the plane indicated by the line 3—3 of Figure 1,

Figure 4 is a detail elevational view of the secondary coil of the heater,

25 Figure 5 is an elevational view of a slightly modified form of the heater,

Figure 6 is a detail sectional view taken on the plane indicated by the line 6—6 of Figure 5,

30 Figure 7 is an elevational view of a further modified form of the heater, and

Figure 8 is an elevational view illustrating a still further modified form of the heater.

The heater is in the form of a transformer 35 comprising a hollow laminated core 1 through which the water to be heated circulates and of which 2 is the inlet and 3 the outlet. The core 1, which provides a closed magnetic path, may be of rectangular 40 contour, as shown, or of any other desired configuration, and consists of a coiled tube made of iron, steel or other suitable metal and bent or casted in the desired shape. The primary winding of the heater comprises

45 coils 4, 5 and 6 which are distributed about the major portion of the core 1 and connected to any suitable source of current supply by leads 7 and 8. The primary coils 4, 5 and 6 may be made of iron or steel wire or

50 tubing or of copper wire or tubing, and are insulated to withstand high temperatures. The secondary winding of the heater consists of a hollow coil 8 which is distributed about the minor portion of

55 the core 1 and through which the water to be heated passes after first passing through

the core. The secondary coil 8 is of the closed circuit type, and the lead 9 connecting the ends thereof is preferably hollow. The lead 9 is in communication with the 60 secondary coil 8 at points adjacent the inlet 10 and outlet 11 thereof. The outlet 3 of the core 1 and the inlet 10 of the secondary coil 8 are in communication and connected preferably by an insulating coupling 12. 65

Current flowing through the primary coils 4, 5 and 6 tend to cause a magnetic flux to circulate through the core 1, and the induced current flowing through the closed circuit secondary coil 8 tends to set up a magnetic 70 flux independent of and opposed to that generated by the primary coils. The current flowing through the primary coils 4, 5 and 6, the current flowing through the closed circuit secondary coil 8, the primary and secondary fluxes circulating through the core 1, and the reaction taking place constantly between these fluxes in the core, heat the water flowing through the core and secondary coil to a high degree in a comparatively 75 short time. As they extend over the major portion of the core 1, the primary coils 4, 5 and 6 tend to confine the reaction between the primary and secondary fluxes to the minor portion of the core, with the result 80 that the greatest possible reaction between the fluxes is attained and such reaction takes place in the immediate vicinity of the secondary coil 8 which is thus heated to a degree higher than the core 1 and subjects the 85 water to the highest temperature as it is leaving the heater. If desired the primary winding may be made of tubing as shown in Figure 8 so as to permit the water to also circulate therethrough, and when so made 90 the ends thereof will be connected to the core 1 and secondary coil 8 through the medium of insulating couplings 13 and 14. The inlet end of the core 1 and the outlet end of the secondary coil 8 are provided 95 with insulating couplings 15 and 16, respectively. As practically all the heat generated in the core 1, primary coils 4, 5 and 6, and secondary coil 8 is utilized, the heater is 100 highly efficient and may be maintained in 105 operation at a comparatively small cost.

The heater shown in Figure 5 differs but slightly from the one shown in Figures 1-4. The core and primary winding of this heater are similar to the corresponding parts of the 110 other heater. Its secondary winding is, however, different, and embodies a main

secondary coil 8^a mounted on the major portion of the core 1 and intimately associated with the primary winding and an auxiliary secondary coil 8^b mounted on the minor portion of the core. The secondary coils 8^a and 8^b are hollow, and are connected to provide a closed circuit secondary by hollow leads 9^a and 9^b. 10^a designates the inlet and 11^a the outlet of this secondary, and the former is connected to the outlet 3 of the core 1 preferably by an insulating coupling 12^a. In this heater, the water passes first through the core 1, then through the secondary coil 8^b and thence through the secondary coil 8^a. 15 As the secondary coil 8^b is heated to a higher temperature than the core 1, and as the secondary coil 8^a is heated to a higher temperature than the secondary coil 8^b, due to the fact that practically all the flux generated 20 by the primary coils 4, 5 and 6 threads the same, the water in passing through the heater is subjected to gradually increasing temperatures.

Excellent results have been attained from 25 the use of the heater shown in Figure 7. This heater differs from the others in that it is not provided with a secondary winding. The core and winding of this heater are similar to the cores and primary windings 30 of the other heaters and are designated by the same reference numerals. An outlet pipe 15 is connected to the outlet 3 of the core 1 of this heater preferably by an insulating coupling 12^b. The current flowing through 35 the coils 4, 5 and 6 of this heater, and the flux generated by the current and circulating through the core 1 of the heater, produces sufficient heat to raise the temperature of water to a high degree during its passage 40 through the core.

From the foregoing description, taken in connection with the accompanying drawings, it will be apparent that the heaters are comparatively simple and inexpensive of manufacture, that they involve no parts apt to get out of order and subject to wear, and that they will rapidly heat water to a high temperature with the use of comparatively little current.

50 What is claimed is:—

1. A fluid heater comprising a tube coiled to provide a laminated hollow core and a circuitous path for the liquid to be heated, and a primary winding on the core.

55 2. A fluid heater comprising a tube coiled to provide a laminated hollow core and a circuitous path for the fluid to be heated, and a primary winding distributed over a greater portion of the core.

60 3. A fluid heater comprising a hollow core having an inlet and an outlet, a primary winding on the core, and a hollow secondary winding on the core and having an inlet and an outlet, the outlet of the core communicating with the inlet of the secondary wind-

ing to permit the fluid to be heated to circulate through both of said parts.

4. A fluid heater comprising a hollow core having an inlet and an outlet, a primary winding on the core and a closed circuit hollow secondary winding on the core and having an inlet and an outlet, the outlet of the core communicating with the inlet of the secondary winding to permit the fluid to be heated to circulate through both of said parts.

5. A fluid heater comprising a hollow core having an inlet and an outlet, a primary winding on the major portion of the core, and a hollow secondary winding on the minor portion of the core and having an inlet and an outlet, the outlet of the core communicating with the inlet of the secondary winding to permit the fluid to be heated to circulate through both of said parts.

6. A fluid heater comprising a hollow core having an inlet and an outlet, a primary winding on the major portion of the core, and a closed circuit hollow secondary winding on the minor portion of the core and provided with an inlet and an outlet, the outlet of the core communicating with the inlet of the secondary winding to permit the fluid to be heated to circulate through both of said parts.

7. A fluid heater comprising a hollow core having an inlet and an outlet, a primary winding on the core, and a hollow secondary winding on different portions of the core and provided with an inlet and an outlet, the outlet of the core communicating with the inlet of the secondary winding to permit the fluid to be heated to circulate through both of said parts.

8. A fluid heater comprising a hollow core having an inlet and an outlet, a primary winding on the core, and a closed circuit hollow secondary winding consisting of communicating coils on different portions of the core and provided with an inlet and an outlet, the outlet of the core communicating with the inlet of the secondary winding to permit the fluid to be heated to circulate through both of said parts.

9. A fluid heater comprising a hollow core having an inlet and an outlet, a primary winding on the major portion of the core, and a hollow secondary winding consisting of communicating coils and provided with an inlet and an outlet, one of the coils being on the major portion and the other on the minor portion of the core, and the inlet of the core communicating with the inlet of the secondary winding to permit the fluid to be heated to circulate through both of said parts.

10. A fluid heater comprising a hollow core having an inlet and an outlet, a primary winding on the major portion of the core, and a closed circuit hollow secondary wind-

ing consisting of communicating coils and provided with an inlet and an outlet, one of the coils being on the major portion and the other on the minor portion of the core, and 5 the outlet of the core communicating with the inlet on the secondary winding to permit the fluid to be heated to circulate through both of said parts.

11. A fluid heater comprising a hollow 10 core having an inlet and an outlet, a hollow primary winding mounted on the core and provided with an inlet and outlets, the inlet of the primary winding communication with the core, and a hollow secondary winding 15 mounted on the core and provided with inlets communicating with the outlets of the primary winding, the secondary winding

being provided with an outlet, and the fluid to be heated passing through the core, and primary and secondary windings. 20

12. A fluid heater comprising a laminated hollow core having an inlet and an outlet, a primary winding on the core, and a closed circuit hollow secondary winding consisting of communicating coils on different portions of the core and provided with an inlet and an outlet, the outlet of the core communicating with the inlet of the secondary winding to permit the fluid to be heated to circulate through both of said parts and both of 25 said parts providing circuitous paths for the fluid. 30

In testimony whereof I affix my signature.
FREDERICK CARLISLE OWEN.
